UNITED STATES PATENT OFFICE

PAUL S. KELLEY, OF GREENSBORO, NORTH CAROLINA

DESIGN FOR A TYPEWRITER TABLE

Application filed April 9, 1930. Serial No. 35,193. Term of patent 3½ years.

To all whom it may concern:

Be it known that I, PAUL S. KELLEY, a citizen of the United States, residing at Greensboro, in the county of Guilford and State of North Carolina, have invented a new, original, and ornamental Design for Typewriter Tables, of which the following is a specification, reference being had to the accompanying drawing, forming part thereof.

The figure is a perspective view of the typewriter table, showing my new design.

I claim:

The ornamental design for a typewriter table, as shown.

PAUL S. KELLEY.
